UNITED STATES PATENT OFFICE.

SIMON OPPENHEIMER, OF NEW YORK, N. Y.

DESIGN FOR A VEIL.

SPECIFICATION forming part of Design No. 22,042, dated December 6, 1892.

Application filed November 8, 1892. Serial No. 451,387. Term of patent 3½ years.

To all whom it may concern:

Be it known that I, SIMON OPPENHEIMER, of New York, in the county of New York and State of New York, have invented and produced a new and original Design for Veils; and I do hereby declare the following to be a full, clear, and exact description of said invention, reference being had to the accompanying drawing, and to the letters of reference 10 marked thereon, which forms a part of this specification.

In the drawing the figure represents a lady's veil having my border design.

The leading feature of the design consists 15 in a series of groups of spots, each group being surrounded by a larger circle of similar spots, the larger circles being contiguous to each other.

The groups of spots are indicated at *a*, and

each consists of a single central spot surrounded by a small circle *b* of similar spots and a larger inclosing circle *c*, also of similar spots. The large circles are contiguous to each other, and on the outer edge of the veil is a curved line of spots partially embracing 25 the larger circle above referred to, and these curved lines meet at their ends, so as to form a festooned line.

What I claim is—

The design for ladies' veils, substantially 30 as shown and described.

In testimony whereof I affix my signature in presence of two subscribing witnesses.

SIMON OPPENHEIMER.
